(57) **CLAIM**

The ornamental design for a safe, as shown and described.

DESCRIPTION

FIG. 1 is a perspective view of a safe showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of encircled portion labeled, “9” in FIG. 1; and,

FIG. 10 is another perspective view thereof, shown in a used condition in an open position.

The equal-length broken lines depict portions of the safe that form no part of the claimed design.

The dash-dot broken lines in FIGS. 1 and 9 illustrate the boundary of the enlarged portion view of FIG. 9 and form no part of the claimed design.
